DESIGN FOR A FOLDING DENTAL CHAIR

Robert C. Angell, Prince Bay, N. Y., assignor to
The S. S. White Dental Manufacturing Company, a corporation of Pennsylvania

Application September 21, 1939, Serial No. 87,321

Term of patent 14 years

To all whom it may concern:

Be it known that I, Robert C. Angell, a citizen of the United States and a resident of Prince Bay, county of Richmond, State of New York, have invented a new, original, and ornamental Design for Folding Dental Chairs, of which the following is a specification, reference being had to the accompanying drawings, forming part thereof.

The drawings represent in Figure 1 a perspective view of the chair as seen from a position forward of the right-hand side thereof showing my new design; and in Figure 2 a front elevational view of the chair as shown in Fig. 1; and in Fig. 3 a rear elevational view of said chair.

I claim:

The ornamental design for a folding dental chair, as shown.

ROBERT C. ANGELL.
